UNITED STATES PATENT OFFICE

102,309

DESIGN FOR AN AUTOMOBILE CARRYING TRAILER

Lynn M. Francis, Birmingham, Mich., assignor
to Mechanical Handling Systems, Inc., Detroit, Mich.

Application September 18, 1936, Serial No. 64,920

Term of patent 14 years

To all whom it may concern:

Be it known that I, Lynn M. Francis, a citizen of the United States, residing at Birmingham,
in the county of Oakland and State of Michigan,
have invented a new, original, and ornamental Design for Automobile Carrying Trailers, of which the following is a specification, reference being had to the accompanying drawing, forming a part thereof.

Fig. 1 is a side elevation, and

Fig. 2 a perspective view of an automobile
carrying trailer embodying my design.

The device is symmetrical in that it presents
the same appearance when viewed from either side thereof.

I claim:

The ornamental design for an automobile
carrying trailer, as shown and described.

LYNN M. FRANCIS.
